UNITED STATES PATENT OFFICE

FRED GRETSCHE, OF BROOKLYN, NEW YORK

BANJO RIM

Application filed November 15, 1928. Serial No. 319,648.

This invention relates to musical instruments, and particularly to an improved banjo, the object being to provide an improved arrangement for holding the parts together properly, while permitting a quick adjustment or quick disassemblage.

Another object of the invention is to provide in a banjo a complete metallic banjo rim having tension screw-receiving sockets formed as an integral part of the rim.

A further object of the invention is to provide in a banjo a special construction including a clamping screw for disengageably connecting the sounding member to the rim.

15 In the accompanying drawings,—

Figure 1 is a plan view of a banjo head with certain parts broken away for better illustrating the invention;

Figure 2 is a side view of the structure shown in Figure 1;

Figure 3 is an enlarged fragmentary sectional view through Figure 1 approximately on the line 3—3;

Figure 4 is an enlarged fragmentary sectional view through Figure 1 on the line 4—4;

Figure 5 is an enlarged perspective view of a banjo rim embodying certain features of the invention;

Figure 6 is a fragmentary detailed perspective view of part of the straining hoop shown in Figure 1.

Referring to the accompanying drawings by numerals, 1 indicates what is commonly known as the resonator of the banjo, and 2 the banjo rim. The rim 2 is adapted to receive the neck of any desired structure so that the usual strings could be properly mounted. As these parts form no part of the present invention they have not been shown, though it is to be understood that the head, as shown in Figures 1 and 2, in actual use is to be provided with the neck, strings and other usual devices forming part of a complete banjo. The rim 2 is metal and is provided with a thickened inwardly-extending portion 3 at the upper end, said portion being somewhat rounded at the upper edge so as to receive the banjo diaphragm 4. This stiffens the rim and practically makes the same unyielding at the upper edge, whereby when the diaphragm

4 is tightly stretched thereon and then caused to vibrate, practically none of the vibrations will be damped by the rim. This results in an exceptionally good, and even brilliant, tone which is especially desirable in instruments of this type. Also, this structure permits staccato notes to be produced accurately and without slurring or muting. The diaphragm is clamped in position by a suitable straining hoop having a flange 6 through which tension bolts 7 extend. The straining hoop or clamping band 5 is provided with a solid section 5' which is positioned to receive the right arm when the instrument is in use. The outer surface of this solid portion is 65 smooth and the edges rounded, so that the arm may slide freely back and forth, as desired. In order to permit this action and at the same time permit the desired number of bolts 7 to be used, the solid section or thickened portion 5' is provided with sockets or counter-sunk portions for receiving the heads of the screws 7. The bolts 7 have preferably square heads so that an instrument may be applied thereon for readily rotating the 70 screws whenever an adjustment of the diaphragm 4 is desired. The screws 7 enter into a threaded socket 8 formed in the enlargement 9 which is integral with the rim 2. As clearly shown in Figure 5, there is an enlargement 9 and a threaded socket 8 for each of the screws 7 and the rim 2 is provided with a radially-extending flange 10 having a depending portion 11. Flange 10 is provided with a number of apertures 12 and around each aperture there is formed a raised bead 13 for receiving the head 14 of a clamping screw 15. The screw 15 is adapted to be screwed into a socket 16 secured in any desired manner to the resonator 1. In Figure 1 there is shown a screw 15 for each aperture 12, but ordinarily two or three screws are all that are needed to hold the resonating member 1 in proper place. It will be noted that the apertures 12 are elliptical and of a size to 75 permit the head 14 to pass therethrough when turned to one position and to straddle when in another position, whereby it will rest on the bead 13. By this construction and arrangement of parts, the resonating member 1 80

can be quickly removed or replaced. Screws 7 may be quickly adjusted or removed, as desired.

What I claim is:—

- 5 1. A banjo, including a head formed with a banjo rim, a diaphragm, clamping means for clamping the diaphragm in position, a resonating member and clamping screws for disengagably securing the resonating member to the banjo rim, said banjo rim having elongated openings for receiving said clamping screws and said screws having elongated heads capable of straddling the openings when in one position and passing through the openings when in another position.
- 10 2. A banjo, including an all-metallic rim having a thickened portion at the diaphragm receiving end, said thickened portion extending inwardly and forming an inner stiffening bead while the outer portion is formed into a straight wall, said rim at the lower part having a radially-extending flange and integral projections provided with threaded sockets.
- 15 3. A banjo, including a diaphragm clamping band, a banjo rim formed entirely of metal, said rim at the lower edge being provided with thickened portions presenting projections, each projection having a threaded socket and a screw for each socket, said screws acting to clamp the diaphragm clamping band in place.
- 20 4. In a banjo, an all-metallic banjo rim having a tubular upstanding portion, a flange extending from one edge of said upstanding portion, said flange having a plurality of elliptical apertures and a plurality of lugs projecting from said tubular portion, said lugs being arranged near said flange, each of said lugs having a threaded aperture.
- 25 5. A banjo, including a banjo rim, a diaphragm, a straining hoop for clamping the diaphragm on the rim, bolts having squared heads extending through part of said hoop for moving the hoop to a clamping position, said banjo rim having a plurality of enlargements, each enlargement having a threaded aperture, said threaded apertures being in line with said bolts, whereby the bolts may be screwed into said apertures for moving said band to a clamping position.
- 30 6. In a banjo provided with a diaphragm, a rim for receiving said diaphragm and a straining hoop for clamping the diaphragm on the rim, a plurality of headed clamping screws for clamping said hoop in position, said hoop being provided with a smooth section against which the arm of a person rests when using the banjo, said smooth section having sockets for receiving the heads of certain of said screws.

Signed at Brooklyn, in the county of Kings and State of New York, this 5th day of November, A. D. 1928.

FRED GRETSCH.
